(No Model.)

S. WILLERSHAUSEN.

SPRING ATTACHMENT FOR PLATFORM ROCKING CHAIRS.

No. 315,870.

Patented Apr. 14, 1885.

UNITED STATES PATENT OFFICE.

SIEGFRIED WILLERSHAUSEN, OF NEW YORK, N. Y.

SPRING ATTACHMENT TO PLATFORM ROCKING-CHAIRS.

SPECIFICATION forming part of Letters Patent No. 315,870, dated April 14, 1885.

Application filed October 2, 1884. (No model.)

To all whom it may concern:

Be it known that I, SIEGFRIED WILLERSHAUSEN, a citizen of the Empire of Germany, residing at New York, in the county and State of New York, have invented new and useful 5 Improvements in Spring Attachments to Platform Rocking-Chairs, of which the following is a specification.

The invention consists in the combination, 10 with the spring, of a bracket provided in its face with a semicircular groove, at both ends of which are formed cheeks, which overlap the end coil of the spring above and below, and a screw for retaining the end coil of the spring 15 in the groove, so that by the cheeks the spring is prevented from revolving in the semicircular groove, and an accidental displacement of the same is effectually prevented. When the spring is secured to the rocker and to the platform of a chair, the cheeks at the ends of the semicircular groove prevent the chair from tipping over sidewise.

In the accompanying drawings, Figure 1 represents a sectional face view of my attachment, 25 the plane of section being indicated by the line $x x$, Fig. 2. Fig. 2 is a transverse section in the plane $y y$, Fig. 1. Fig. 3 is a perspective view of the bracket detached.

Similar letters indicate corresponding parts. 30 In these drawings, the letter A designates one of the rockers of a rocking-chair, and B is one of the side rails of the platform which supports the rockers. On the inside of the rocker is secured the bracket C, and on the inside of the side rail is fastened a similar bracket, C', and these brackets are connected by the spring D. Each of the brackets is provided in its face with a semicircular groove, a , at the ends of which are formed cheeks $b b'$, and which is intended to receive the end coil, e , of the spring D. When the end coil is placed into the semicircular groove, the cheeks $b b'$ overlap the coil above and below. A screw, d , serves to secure the end coil of the spring in 35 the groove a . This screw also assists in securing the bracket to the rocker or to the side rail.

By referring to the drawings it will be seen that the cheeks $b b'$ overlap the end coil of the 40 spring above and below, and by these means the spring is prevented from turning in the semicircular groove in a vertical plane, or

round an imaginary horizontal axis running parallel to the face of the rocker and drawn through the center of that portion of the semicircular groove which is nearest the face of the rocker. By referring to Fig. 2 it will be seen that if the cheek b' is taken away the spring can turn in the direction of arrow 1 round an axis formed by that portion of its end coil 55 which is situated beneath the screw d . If no provision is made to prevent the motion, and the spring is secured to a rocking-chair, the spring is liable to become detached from its brackets whenever the chair is slightly tilted 60 sidewise during the operation of rocking. This difficulty is effectually overcome by providing the semicircular groove with the overlapping cheeks $b b'$. My attachment also has the great 65 advantage that the spring can be readily detached from its brackets at either end simply by removing one of the screws d , for as soon as this screw is taken out the end coil of the spring previously retained by said screw can be readily forced out of the semicircular groove 70 without disturbing the other end of the spring. For this reason my attachment can be easily fastened to a rocking-chair, simply by first attaching the brackets in the proper position to the rockers and to the side rails of the platform, and then forcing the end coils of the 75 springs into the semicircular grooves of the brackets and securing the same in position by screws d .

I am aware of the Patents Nos. 247,472, dated 85 September 27, 1881, and 297,108, dated April 22, 1884. The former shows a bracket which has a semicircular ledge for supporting the end coil of the spring and a screw for retaining the end coil on the ledge. This device lacks 90 the cheeks $b b'$, which are essential to produce a secure connection between the bracket and the spring.

In Patent No. 297,108 a bracket is described 95 which has a spiral ledge that passes between the first and second coils of the spring.

In order to secure the spring in position it must be turned round, and if the spring is secured to a rocking-chair neither end can be detached from its bracket independent of the 100 other.

What I claim as new, and desire to secure by Letters Patent, is—

1. The combination, substantially as herein-

before described, with the rockers of a chair and with its platform, of the spring D, the brackets C C', the semicircular grooves formed in said brackets, the cheeks b b', formed at the 5 ends of said grooves, and the screws for retaining the end coils of the spring in the semicircular grooves.

2. The combination, substantially as hereinbefore described, with the spring D, of the 10 brackets C C', the semicircular grooves formed in the brackets, the cheeks b b', formed at the

ends of the semicircular grooves, and the screws for retaining the end coils of the springs in the grooves.

In testimony whereof I have hereunto set my 15 hand and seal in the presence of two subscribing witnesses.

SIEGFRIED WILLERSHAUSEN. [L. s.]
